UNITED STATES PATENT OFFICE.

ERNEST O. LINTON AND FRANK J. BLUM, OF KENOSHA, WISCONSIN.

OIL-GAS PRODUCER AND BURNER.

1,233,676.

Specification of Letters Patent. Patented July 17, 1917.

Application filed November 10, 1915. Serial No. 60,730.

To all whom it may concern:

Be it known that we, ERNEST O. LINTON and FRANK J. BLUM, citizens of the United States, residing at Kenosha, in the county 5 of Kenosha and State of Wisconsin, have invented certain new and useful Improvements in Oil-Gas Producers and Burners, of which the following is a specification.

Our invention relates to an oil-gas producer and burner and has for its object to produce an apparatus in which liquid fuels, such as crude petroleum, fuel oil, and kerosene, will first be gasified or vaporized, and then burned under such conditions that 10 there is provided a supply of oxygen sufficient to insure complete combustion. A further and principal object of our invention is to so combine the various elements of the device that there is produced a flame of 15 exceedingly high temperature, either oxidizing or reducing as desired, and of large volume with a minimum consumption of fuel.

A further object of our invention is to provide means for readily controlling and 20 adjusting the temperature of the coil or retort in which the fuel is vaporized or gasified, and to provide means for heating such coil or retort by a non-oxidizing or neutral flame, corrosion of the coil or retort being 25 thereby avoided.

It is a still further object of our invention to provide a device of novel mechanical construction for producing a gas from heavy hydrocarbon fuel and burning the thus-produced gas without any deposit of carbon 30 either inside or outside the burner.

These objects we attain by the construction shown in the accompanying drawings, in which,—

40 Figure 1 is an elevation of the device, parts being shown in section;

Fig. 2 is a transverse section of Fig. 1 on the plane II—II;

Fig. 3 is a detail view in elevation of the 45 burner tube; and

Fig. 4 is a transverse section of Fig. 3 on the plane IV—IV of Fig. 3.

The fuel is delivered under pressure to the pipe 16 from a tank (not shown) provided 50 with a pressure connection to the compressed-air main, air being delivered to the burner through pipe 11 and a control valve 10. The oil is delivered to pipe 16, having

a control valve 15, from which the oil passes into a pipe 9, which extends from a considerable distance into the surrounding air pipe 8, as *e. g.* five to ten times the inner diameter of the air pipe 8. This pipe 8 passes into the inside of an open-ended casing 1, preferably cylindrical in shape, and 55 is there continued in the form of a coil 8' having several convolutions from which coil it is connected by pipe 8'', through a return pipe, to the gas-nozzle 7. The gas-nozzle 7 projects into a burner-tube 2, which is supported by the spider ring 21 carried by the arms 20 connected to the casing 1. To the gas-nozzle is secured, at its inner end, an air intake cap 5, having a series of air openings 5' ; this cap 5 being in turn secured to a 60 guide-tube 6 surrounding and sliding on the gas-nozzle 7. The burner tube 2, gas-nozzle 7 and perforated cap 5 form a Bunsen burner. The burner-tube 2 has at its outer end a gas baffle 4, preferably constructed, as 65 shown in Fig. 1, to form an annular pocket or chamber between its inner end portion and the inner wall of the gas-nozzle 7. A short distance to the rear of this gas baffle 4, which serves to cause a rebound or reflux 70 of some of the outwardly flowing mixed gas and air, the burner tube 2 is provided with a series of rearwardly inclined slots 3, through which this refluxed mixture may 75 escape and burn within the annular space 80 between the casing 1 and burner tube 2 and heat the coil 8' located in this space. The gas issuing from the slots and the flame resulting from its combustion are given a 85 backward whirling motion, and may extend 90 to the rear of the casing 1, or as far therein as may be desired. The slots 3 are preferably made by cutting, as with a saw, the plane of the saw being at an angle of about 95 30° to the axis. A circumferential series of such cuts are made, the planes of the adjoining cuts being at a very obtuse angle to each other. In practice, we have found that with a casing of five inches internal diameter, and a burner-tube of 2½ inches in diameter, 100 five slots, about 2½ inches long and $\frac{3}{16}$ inch wide, in each circumferential series and two of such series extending together over about four inches lengthwise of the pipe are sufficient to produce the effect desired, which 105 will be later described. An additional sup-

ply of compressed air is delivered to the gas nozzle 7, from pipe 12 which is connected to the main pressure air-supply pipe 11. The flow through pipe 12 is controlled or 5 adjusted by valve 13.

The operation of the device is as follows: Oil under pressure is delivered through the spray-pipe 9 into the stream of air under pressure flowing through the pipe 8. The 10 mixed oil and air pass through the coil 8', where they are subject to a temperature sufficient to vaporize or gasify the oil, the coil being heated to such temperature, say from 700°-900° by the combustion of the 15 gas mixture issuing from the slots 3. Owing to the backward inclination of these slots, the gases and the resulting flame are given a rearward whirling motion. The heated mixed gases, with the additional air 20 delivered through pipe 12, flow under high pressure through the gas-nozzle 7, from which they expand into the burner-tube 2. The main body of the combustible mixture passes out of the end of the burner-tube and 25 burns with a blue flame. The high velocity at which the gases are delivered from the pipe 7 causes additional air to be drawn in through the openings 5' in the cap 5. By proper adjustment of the oil and air supply, we are enabled to produce a high velocity blue flame of large volume and are thus 30 enabled to deliver a large number of heat units at a rapid rate, whereby a very high temperature may be produced and maintained. We have found in practice that an air pressure of from 25 to 100 pounds per 35 inch may be successfully used.

The proper temperature of the flame within the space between the burner-tube 40 2 and casing 1 may be controlled by sliding the burner-tube toward or from the casing. If it is moved rearwardly, as to the position shown in full lines, the temperature of this coil-heating flame is increased, as this flame 45 then strikes more or all of the heating coils; by moving the burner-tube farther into the casing the temperature of the coil-heating flame is reduced, as a smaller number of the heating coils lie within the flame. If 50 the coil 8' begins to show a tinge of red, the temperature is becoming too high and the burner pipe is accordingly moved forward, and the temperature of the coil reduced. If from the appearance of the main flame or 55 other indications, the oil is not being completely gasified, the burner pipe is slid backward and the temperature of the coil thereby increased.

While the main heating flame is an exceedingly hot blue flame, oxidizing in character, the coil heating flame is non-oxidizing or neutral in character, and therefore has no tendency to oxidize or corrode the heating coil, nor is there any objectionable

deposit of carbon or soot. By forcing the 65 oil and vapor through the tube 8 by compressed air, the speed of the mixed gases is such that there is no possibility of any deposit of carbon in the coils 8' and pipe 8''. The additional air from pipe 12 assures 70 a sufficient supply of oxygen and breaks up any possible particles of oil remaining and makes the mixture perfect. There is thus provided an ample supply of air and the necessity for a prohibitively 75 large heating coil is obviated.

An exact control of all the conditions essential to the production of complete combustion is therefore provided.

Our burner is available for heating steam-boilers, japan kilns, annealing ovens, furnaces for melting metals such as steel or brass, etc.

While we have shown a specific form of apparatus, our invention is not restricted 85 to the particular details of form and size shown and described, as equivalent devices may be used to produce the same results.

We claim:—

1. A Bunsen burner comprising a gas-nozzle and a burner-tube having at its exit end an annular baffle, said tube having openings therein, a coil surrounding said tube in proximity to said openings and connected to said gas-nozzle, means for longitudinally adjusting said burner-tube, and means for supplying a combustion supporting agent and fuel under pressure to said coil.

2. A Bunsen burner comprising a gas-nozzle and a burner-tube having at its exit end an annular baffle, said tube having rearwardly-extending openings therein, a coil surrounding said tube in proximity to said openings and connected to said gas-nozzle, means for longitudinally adjusting said burner-tube, and means for supplying a combustion supporting agent and fuel under pressure to said coil.

3. A Bunsen burner comprising a gas-nozzle and a burner-tube having at its exit end an annular baffle, said tube having rearwardly-extending openings therein arranged at an acute angle to the axis of the burner-tube, a coil surrounding said tube in proximity to said openings and connected to said gas-nozzle, means for longitudinally adjusting said burner-tube, and means for supplying a combustion supporting agent and fuel under pressure to said coil.

4. A Bunsen burner comprising a gas-nozzle and a burner-tube having at its exit end an annular baffle, said tube having rearwardly-extending slots therein arranged at an acute angle to the axis of the burner-tube, a coil surrounding said tube in proximity to said slots and connected to said gas-nozzle, means for longitudinally adjusting

- said burner-tube, and means for supplying a combustion supporting agent and fuel under pressure to said coil.
5. A Bunsen burner comprising a gas-nozzle and a burner-tube having at its exit end an annular baffle, said tube having openings therein, a coil surrounding said tube in proximity to said openings and connected to said gas-nozzle, an open-ended 10 casing surrounding said coil, means for longitudinally adjusting said burner-tube, and means for supplying a combustion supporting agent and fuel under pressure to said coil.
- 15 6. A Bunsen burner comprising a gas-nozzle and a burner-tube having at its exit end an annular baffle, said tube having rearwardly-extending openings therein arranged at an acute angle to the axis of the burner-tube, a coil surrounding said tube in proximity to said openings and connected to said gas-nozzle, an open-ended casing surrounding said coil, means for longitudinally adjusting said burner-tube, and means for supplying a combustion supporting agent and fuel under pressure to said coil.
- 20 7. A Bunsen burner comprising a gas-nozzle and a burner-tube having at its exit end an annular baffle, said tube having rearwardly-extending slots therein arranged at an acute angle to the axis of the burner-tube, a coil surrounding said tube in proximity to said slots and connected to said gas-nozzle, an open-ended casing surrounding said coil, means for longitudinally adjusting said burner-tube, and means for supplying a combustion supporting agent and fuel under pressure to said coil.
- 25 8. A Bunsen burner comprising a gas-nozzle and a burner tube having a peripheral gas-baffling exit, said tube having there-in rearwardly-extending openings arranged at an acute angle to the axis of the burner-
- tube and a coil surrounding said tube in proximity to said openings and connected to said gas-nozzle.
9. A Bunsen burner comprising a gas-nozzle and a burner tube having a peripheral gas-baffling exit, said tube having there-in rearwardly-extending slots arranged at an acute angle to the axis of the burner-tube and a coil surrounding said tube in proximity to said slots and connected to said gas-nozzle.
10. A Bunsen burner comprising a gas-nozzle and a burner tube having a peripheral gas-baffling exit, said tube having there-in rearwardly-extending openings arranged at an acute angle to the axis of the burner-tube, a coil surrounding said tube in proximity to said openings and connected to said gas-nozzle, and an open-ended casing surrounding said coil.
11. A Bunsen burner comprising a gas-nozzle and a burner tube having a peripheral gas-baffling exit, said tube having there-in rearwardly-extending slots arranged at an acute angle to the axis of the burner-tube, a coil surrounding said tube in proximity to said slots and connected to said gas-nozzle, and an open-ended casing surrounding said coil.
12. A Bunsen burner comprising a gas-nozzle and a burner-tube, openings in said tube, means within the burner tube to cause a portion of the gases to pass out of said openings, a coil surrounding said tube in proximity to said openings and connected to said gas nozzle, and means for adjusting the relative positions of said openings with reference to the coil.

In testimony whereof, we affix our signatures.

ERNEST O. LINTON.
FRANK J. BLUM.
